UNITED STATES PATENT OFFICE.

JAMES BRANNEN, OF PHILADELPHIA, PENNSYLVANIA.

EXTENSION-CHANDELIER.

SPECIFICATION forming part of Letters Patent No. 285,963, dated October 2, 1883.

Application filed March 15, 1883. (No model.)

To all whom it may concern:

Be it known that I, JAMES BRANNEN, a citizen of the United States, residing at Philadelphia, in the county of Philadelphia and State 5 of Pennsylvania, have invented certain new and useful Improvements in Sliding or Extension Chandeliers and Drop-Lights; and I do hereby declare the following to be a full, clear, and exact description of the invention, reference being had to the accompanying drawings, which form part of this specification, in which—

Figures 1 and 2 are side views. Fig. 3 is a cross-section, and Fig. 4 is a modification.

My invention has relation to sliding drop-lights, and has for its object the provision of means whereby the moving portion or harp may be readily and easily moved either up or down and caused to remain at any desired height, being retained in an adjusted position 20 by friction on the sliding pipe, which friction is relieved, wholly or in part, when said harp is elevated or moved upwardly.

In Letters Patent granted to me dated July 1, 1873, No. 140,459, is shown and described a 25 device for supporting the sliding pipe of a drop-light, consisting of a spring-actuated eccentric that pressed upon said pipe and held it in position, being caused to release its grasp by pulling a cord attached to the periphery of said eccentric, the harp being then raised or drawn down, as desired.

My present invention, which is an improvement upon said patented invention, consists of means whereby a sliding pipe is sustained in 35 position by grooved rollers which are pressed against the said pipe by springs attached to pivoted bars arranged in such manner that a downward movement of the pipe increases the pressure or tension of the springs and the friction 40 of the rollers, while an upward movement of said pipe diminishes such pressure and friction.

Referring to the accompanying drawings, A represents the stationary pipe of a chandelier or other fixture, and B the extension or drop-light pipe, fitted and adapted to slide up and down in the same. The extension-pipe B is preferably square in cross-section, and is designed to support a harp or other like device at its lower end. To the lower end of the stationary pipe A is attached a rectangular frame or body, A', having the top *a*, bottom *b*, and sides *c c*.

C C represent two metal bars, which are pivotally attached to the top *a* of the frame A', having pins *d* at their lower extremities, to 55 which are secured the ends of two spiral springs, *e e*, one on each side of the extension-pipe B. The tendency of the springs *e e* is to draw the lower ends of the bars C C together, and the inward movement of said bars is limited by 60 stops *f f* on the bottom *b* of the frame.

D D represent friction-rollers having each a V-groove in their periphery, that press against and partly embrace the extension-pipe B. The rollers D D are located between the extension-pipe B and the pivoted rods C C on either side, and are of such size that when they are at their highest point, as shown in Fig. 1, they will fit loosely in position, and will only lightly bear upon the extension-pipe. When, however, the 70 pipe is drawn downward, the rollers spread or move the rods C C outwardly against the influence of the springs *e e*, and are pressed strongly against the extension-pipe by the tension or pressure of said springs. When the 75 rollers meet the stops *f f* their further rotation is thereby prevented or retarded while the pipe B is descending, thus increasing the friction upon said pipe.

In Fig. 4 I have shown a slight modification 80 of my invention, wherein the bars C C are pressed inward by flat springs *g g*, secured to the sides *c c* of the frame, said flat springs being substituted for the spiral springs *e e*.

The operation of my invention is as follows: 85 When it is desired to lower the harp or drop-light, it is drawn downwardly by hand or otherwise. The friction of the pipe B upon the rollers D D causes them to revolve and descend until they come in contact with the stops 90 *f f*, spreading the rods C C apart, thereby increasing the tension of the springs and causing said rollers to bear with increasing pressure on the pipe B. When the rollers meet the stops *f f*, their revolution is thereby prevented or retarded. Any further downward draft upon the extension-pipe will cause the same to move upon the rollers with considerable friction, and said pipe will be retained by such friction at any desired place where the downward pull thereon is suspended. When the extension-pipe is raised, by pushing it upwardly, the rollers move to their upward position, 95 where the friction is slight, thus permitting 100

the harp or drop-light to be elevated with ease. After raising the harp and letting go of it, its weight and that of the pipe causes it to drop slightly until the rollers meet the stops *f f*, in 5 which position the friction is sufficient to sustain the pipe and its appendages. The square form of pipe is preferable, as in such case it passes through a hole of similar shape in the frame and keeps the harp or other fixture in a 10 uniform position, and for the further reason that it affords a better grip to the friction-rollers.

While I have described the invention as being applied to a gas-fixture, it is equally applicable to a drop-light of any description, 15 whether gas be used or not, and where it is not desired to use it in connection with a gas-fixture a solid rod may be substituted for the pipe.

What I claim as my invention is as follows:

1. In an extension-chandelier, the combina-

tion, with the stationary pipe *A*, having the 20 frame *A'*, and the pivoted bars *C C*, attached to said frame, of the sliding pipe *B*, rollers *D* located between said sliding pipe and pivoted bars *C C*, and the springs *e e*, connecting said pivoted bars together, substantially as 25 described.

2. The combination, with the stationary pipe *A* and frame *A'*, attached thereto, of the pivoted bars *C*, extension-pipe *B*, rollers *D D*, and suitable springs for pressing said bars against 30 the rollers, substantially as described.

In testimony that I claim the foregoing I have heremunto set my hand this 9th day of March, 1883.

JAMES BRANNEN.
